UNITED STATES PATENT OFFICE.

WILLIAM C. PAUL AND OSCAR D. KLEINSTEUBER, OF MILWAUKEE, WISCONSIN, ASSIGNORS OF ONE-THIRD TO THOMAS K. EWING, OF SAME PLACE.

RAILWAY-SIGNAL.

SPECIFICATION forming part of Letters Patent No. 396,365, dated January 15, 1889.

Application filed July 21, 1887. Serial No. 244,868. (No model.)

To all whom it may concern:

Be it known that we, WILLIAM C. PAUL and OSCAR D. KLEINSTEUBER, of Milwaukee, in the county of Milwaukee, and in the State of Wisconsin, have invented certain new and useful Improvements in Devices for Operating Railway-Signals by Electricity; and we do hereby declare that the following is a full, clear, and exact description therof.

10 Our invention relates to signals for railroad-switches and means for operating them by electricity, and will be fully described hereinafter.

In the drawings, Figure 1 is a vertical longitudinal section of the mechanical portion of our invention. Fig. 2 is a vertical transverse section of the same with the magnets removed and the upper portion of the tower broken away; Fig. 3, a front view; Fig. 4, a plan view with the tower in horizontal section, Fig. 5, a section on line 5 5 of Fig. 1. Fig. 6 is a diagram; Fig. 7, an elevation of an annunciator-box forming part of our invention; and Fig. 8 is a detail. Fig. 9 is a vertical sectional view through a signal-tower of somewhat modified construction, and Fig. 10 is a section on the line 10 10 of Fig. 9.

A is the signal-tower, and B is the casing that contains the mechanism for raising the 30 signals.

C is a bell-crank lever that is pivoted in the upper portion of the casing. One arm, C', of the lever C extends downward and is connected by a link, D, with the curved short 35 arm of a lever, D', that is pivoted to the upper front corner of the casing B, and the long arm of this last-named lever carries a day-signal, E, as shown in Fig. 1. The other arm, C', of lever C extends through a slot, a, into 40 tower A, where it is jointed by a slot and pin to the standard F of the upright signal-cage F', which latter is arranged to slide up and down in the lamp-frame c, which is provided with the usual lenses, c'. The lamp (not 45 shown) is carried by a cup, d, that in turn is supported by the rods b. The cage F' is fitted with the usual colored glasses, F², that are used for signaling at night.

K is a weight that is suspended in the tower 50 A by a rope or chain, K', one end of which is

attached to the tower at m, while the other, passing over a pulley, m', is wound about a drum, L, at one end of which is a cog-wheel, L'. The cog-wheel L' is loose upon the shaft O of the drum, but carries a pawl, N, that is held down upon the teeth of a ratchet, N', on shaft O, by a spring, N², and this ratchet is keyed to the shaft O. The cog-wheel L' is geared to the shaft M of another cog-wheel, P, by a pinion, p, and this to the shaft q' of another cog-wheel, q, by a pinion, q², and the shaft q' of cog-wheel q to a pinion, R, on the shaft R' of a wrist-wheel, R². The shaft q' carries a cam-wheel, S, that has an abrupt shoulder, S', that faces to the left, and the shaft R' carries another cam-wheel, T, having an abrupt shoulder, T', that faces to the right.

U is a lever that is pivoted at one end to a stand, u, that is in turn bolted to the casing, 70 while its other end, which is shouldered at v, rests on the cam-wheel S.

The lever U is of metal and forms an armature for electro-magnets W W, that are wired to binding-posts w w, and thence by 75 wires W' through battery Q and a similar signal-stand and casing, A', at the opposite approach to the switch Y of a railroad-track, and thence by wire W² to a contact-piece, X, on the switch-stand z, while wire W³ connects its 80 binding-post to a contact-point, X', on the switch-stand.

The wrist-wheel R² is wristed to one end of a metal strap, r, the other end of which is pivoted to the arm C' of lever C, as shown in 85 dotted lines, Fig. 1, and full lines, Fig. 2.

The operation of my device is as follows: The switch-lever z is formed with an insulated metallic projection, z', which, when the switch is open, will make connection between the 90 contact-pieces X X' and establish a current through the wires W² W³ W' and the electro-magnets W W of the signal-stands, thus energizing the magnets in each stand, when the magnets will lift lever U and release cam-wheel S. The weight will now set the gearing in motion, and the wrist-wheel R² will draw on the strap r and arm C' of lever C, and arm C', drawing on strap D, will tip lever D' and throw the day-signal out of the casing, 95 100

while at the same time the arm C^2 will lift the night-signal frame F' , so as to inclose the lamp by the colored glasses F^2 . This is done by a half-revolution of wheel R^2 , for as the latter completes a half-revolution the notch T' of cam T will engage the upper portion of the head v of the armature U and stop the machinery until the switch Y is closed, when the breaking of the circuit thereby will de-
 5 magnetize the electro-magnets W and permit a spring, U' , to draw the head v of armature U out of engagement with notch T' , and thus again release the gearing, which again making a half-revolution will return the signals to the position shown in full lines, Fig. 1, with the head v of the armature in engagement with the notch S' of cam S , in which position the parts will remain until circuit is again closed by the opening of the switch.
 10 It is obvious that the gearing may be released to expose the signals by a broken circuit by simply changing the relation of the notches in the cams S and T to each other and changing the position of contact-points X X'
 15 accordingly.
 In order to apprise the switch-tender of the position of the switch or signal, we place an annunciator-box, h , in the circuit between one of the signal-stands and battery Q , the
 20 interior of which box is shown in Fig. 7, wherein h' is an electro-magnet, h^2 its armature, which is pivoted to the magnet-frame i , and has a pendent arm, i' , which is connected by a link, J^2 , with the short arm of a lever, j ,
 25 that is pivoted near the lower end of the box, and to the long arm of this lever is attached a plate bearing the words "open" "closed." The lever j is suitably guided at the top, and the armature h^2 carries on its upper end the
 30 stem of a clapper, j' , that strikes a bell, j^2 , when said armature closes on the magnets.
 J^3 is a regulator for the armature, and J^4 a regulator for the lever j . The electric switch G is for breaking circuit and raising the signals independently of the railway-switch.
 35 If the signals are raised by a closed circuit, as shown in the drawings, the word "open" will precede the word "closed," if by an

open circuit the word "closed" will be placed
 50 first.

It is evident that without departing from the spirit of our invention the glasses may be lifted above the lamp to expose it, and drawn down over the lamp to inclose it, as shown in detail in Figs. 9 and 10, wherein the signal-cage F' is extended by standards F^3 , so that normally (or when the magnets are de-energized) the signal-glasses F^2 will inclose the lamp, and then when the magnets are energized said glasses F^2 will be lifted above the 60 flame of the lamp, as in Fig. 9, the operation being just the reverse of that of the device shown in Fig. 1.

Having thus fully described our invention, what we claim as new, and desire to secure by 65 Letters Patent, is—

1. The combination, with a day and night signal and suitable gearing, of two cam-wheels facing in opposite directions and arranged one above the other, an electro-magnet, and an armature-pawl, one end of which is pivoted to the casing and the other having a head adapted to engage alternately with the notches of the respective cam-wheels, a wrist-wheel carried by the shaft of one of the cam-wheels, a link wristed to said wrist-wheel, and a bell-crank lever connected by said link with the wrist-wheel and toggled to the day and night signals, substantially as described.
 70

2. The combination, with the electro-mag- 80 net and its pivoted armature having a double catch-head on its free end, of two oppositely-faced cam-wheels, and clock-work gearing for driving them, a wrist-wheel carried by the shaft of one of the cam-wheels, and levers 85 linked to said wrist-wheel and to the signals, substantially as described.

In testimony that we claim the foregoing we have hereunto set our hands, at Milwaukee, in the county of Milwaukee and State of Wisconsin, in the presence of two witnesses.
